UNITED STATES PATENT OFFICE.

BENJAMIN F. KELLEY, OF TULSA, OKLAHOMA, ASSIGNOR OF ONE-FOURTH TO R. A. GRIFFITH AND ONE-FOURTH TO D. D. MYERS, BOTH OF TULSA, OKLAHOMA.

CLAMP.

1,234,038.

Specification of Letters Patent. Patented July 17, 1917.

Application filed November 11, 1916. Serial No. 130,879.

To all whom it may concern:

Be it known that I, BENJAMIN F. KELLEY, a citizen of the United States, residing at Tulsa, in the county of Tulsa and State of Oklahoma, have invented new and useful Improvements in Clamps, of which the following is a specification.

This invention relates to an improvement in clamps and is intended for use in holding the line or cable to which is attached the tools in drilling deep wells of every description.

The clamp is adapted to be suspended below the temper screw by links and is adapted to hold the line or cable so firmly that the weight of the tools cannot slip the line through it so that the tools can only descend as fed out by the temper screw.

A simple and satisfactory embodiment of the improvement, as it now appears to me, is exemplified by the accompanying drawings, in which:

Figure 1 is a front elevation of a clamp constructed in accordance with the present invention,

Fig. 2 is a top plan view of the same, the suspending links being removed,

Fig. 3 is a sectional view approximately on the line 3—3 of Fig. 1,

Fig. 4 is a sectional view approximately on the line 4—4 of Fig. 1,

Fig. 5 is a sectional view approximately on the line 5—5 of Fig. 1,

Fig. 6 is a sectional view approximately on the line 6—6 of Fig. 2,

Fig. 7 is a sectional view approximately on the line 7—7 of Fig. 2,

Fig. 8 is a perspective view of one of the jaws, and

Fig. 9 is a similar view of one of the removable rope slips associated with the jaws.

The clamp in the construction illustrated is in the nature of what is generally known in the art as a three-piece clamp and includes a back member which is substantially C-shaped in plan and which is in the nature of a socket, the said back being indicated by the numeral 1. The member 1, from what I will term its inner face is channeled or otherwise formed with a pocket 2 disposed a suitable distance from the opposite ends of the casting, the inner wall of the pocket being rounded to conform to the outer contour of the casting, and the side walls of the pocket being concaved, as at 3, while the

corners provided by the said side walls are preferably rounded as clearly disclosed by the drawings.

The jaws are indicated by the numerals 5 and 6 respectively and each of the said jaws is of a substantially similar construction, the same having their rear or inner ends formed with extensions in the nature of knuckles 7—7, the outer surface of the knuckles being rounded and the outer surface of the knuckles being of an arcuate formation and the sides of the same being rounded providing the corners of the knuckles with what may be termed beads 8. The knuckles are adapted to be received in the pocket of the casting 1 and the beads 8 are adapted to engage with the rounded side walls provided by the pockets. The inner faces of the knuckles are straight, except for the outer edges thereof which are inclined away from each other and the said inner straight faces are each provided with registering curved depressions extending the entire length of the said knuckles and these depressions are adapted to receive a pin 9 which passes through a suitable opening 10 in one or both of the end walls of the casting or socket member 1, and by this arrangement it will be noted that the jaws 5 and 6 are hingedly secured to the back casting or socket member. Each of the jaws, outward of the knuckle 7, and at the portion thereof projecting outwardly of the pocket of the casting 1 is widened and upon the upper surface of the said widened portions, adjacent to the said knuckles there are formed hook members 10, each of said hooks adapted to receive the end member of a plurality of links 11—11 whereby the device may be suspended below the temper screw of the drilling apparatus (not shown).

The straight inner faces of the knuckles may communicate with similar substantially straight faces 13 upon the inner surfaces of the jaws 5 and 6, but the said jaws from the referred to straight surfaces 13 are gradually flared outwardly to the ends of the said jaws. The surfaces 13, inwardly of the hooks 10, of each of the jaws 5 and 6 are provided with alining substantially rectangular slots or grooves 14—14, and each of said grooves adjacent to the lower end thereof has its inner wall formed with a substantially V-shaped notch 15, the upper wall of which being straight and the inner

wall being inclined. The grooves 14 are adapted to receive the substantially rectangular body portions of rope slips 16, the same having their inner faces provided with 5 rounded grooves 17 extending longitudinally therethrough whereby to receive the rope. Each of the rope slips 16 is provided with a substantially V-shaped tongue 18 that is adapted to be received in the notch 15 while the upper end of each of said rope slips has its sides for a determined length provided with ribs 19, and these ribs are adapted to be received for a portion of their length in depressions 20 provided in the side 10 walls of the groove 14. By this arrangement it will be noted that the rope slips 16 may be moved downwardly of the jaws 5 and 6 through the groove 14 and the ribs 19 are received within the depressions 20, when 15 the tongue 18 will be disposed opposite the notch 15 and by an inward pressure be received in the said notch. This method of securing the rope slips to the jaws is an important feature of the invention as in all 20 other constructions with which I am acquainted, securing means are provided between the rope slips and the jaws which are independent of both the rope slips and the jaws and are generally in the nature of 25 screws or the like. It will be apparent that to attach or remove the rope slips with such a construction time and labor are required, while with a construction as just described the rope slips may be readily inserted 30 within the jaws or easily removed therefrom as desired.

Each of the jaws, 5 and 6, at the outer end thereof, is centrally provided with a transverse slot or opening 21, and the said jaws, 40 upon their outer faces and to the opposite sides of the said opening are formed with concaved enlargements 22-22. Within each of these concavities is adapted to be received the longitudinal portions 23-23 45 of T's 24 and 25 respectively. The longitudinal member of the T 24 is of a materially greater length than that of the member 22 of the T 25, and the said longitudinal member of the T 25 is adapted to be received in the concavities 23 of the jaw 5 and 50 to project beyond the opposite ends of the said jaw. The member 23 at the portion thereof in a line with the upper and lower edges of the jaw is provided with transverse 55 rounded openings 26-26, and the transverse or central member 27 of the T 24 is adapted to be received in the notch or cut away portion 21 of the said jaw 5. The central portion 28 of the T 25 is adapted to 60 be received in the notch or cut away portion 21 of the jaw 26 and the longitudinal member 23 thereof is adapted to be received in the lower portions of the concavities 22 of the said jaw 6. The enlargements provided 65 by the concavities 22 upon the jaws 6 pro-

ject only a slight distance above the opposite longitudinal edges provided by the notch or cut away portion 26 in the said jaw which to the opposite edges of the jaw in a line with the said concavity is formed with 70 outwardly extending ears 29-29, the same being provided with openings through which pass hinge bolts 30-30 that have their ends reduced, as at 31, to engage in the threaded bores 32 at the ends of the 75 longitudinal member 23 of the T 24. The bolts 30 are also adapted to pass through eyes 31' formed upon one of the ends of guide rods 32', the said guide rods being disposed transversely over the ears and 80 having their ends passed through the openings 26 in the longitudinal member 23 of the T 24. The members 23 and 24 are each centrally bored, the said bore passing through the members 27 and 28 and each 85 of these bores is provided with threads, the threads of the bore of the member 24 being at a different pitch or angle from the threads in the member 25.

The numeral 33 designates the adjusting 90 member or bolt, the same from its center being provided with oppositely pitched threads 34 and 35, and the said member having one of its ends secured to an operating handle 36. It is, of course, to be understood 95 that the oppositely pitched threads of the bolt 33 engage with the registering pitched threads in the members 24 and 25 and by operating the handle 36 it will be noted that the jaws may be brought toward or away 100 from each other whereby to effectively clamp the rope in the rope slips 16 so that the clamp may be effectively sustained upon the said rope or line or the rope or line may be permitted to pass in or out of the clamp. 105

By hinging the jaws and by operating the same through the medium of a right and left hand screw and the elements connected with the jaws and screws, it will be noted that a great amount of power will be imparted to the clamp, that the construction is such as to insure the positive operation of the parts and a great strength to the construction. It will be further noted that in lieu of the single long link now commonly 110 employed in attaching the clamp to the temper screw, I employ at least three links so that a greater flexibility is afforded the attaching and suspending means as well as permitting of the more easily handling of 115 the device, and it is thought that from the above description taken in connection with the drawings the description will be deemed sufficient to enable others skilled in the art 120 to which this invention appertains to fully understand the mechanical construction and the method of operation thereof.

Having thus described the invention, what I claim is:

1. A clamp for the purpose set forth in- 130

- cluding a flexible suspending means, a back member having a central pocket, jaws having their ends provided with knuckles received within the said pocket to hingedly connect the jaws with the said back member, means between the back member and the meeting faces of the knuckles for retaining the knuckles within the socket and the jaws hingedly connected with the back member, removable rope slips for each of the jaws, and means disposed transversely of the free ends of the jaws and operable to relatively adjust the same and to hold the same in such adjusted position. 5
- 15 2. A clamp for the purpose set forth including flexible supporting means, a back member having a central pocket, the side walls of which being rounded, two jaws each having one of their ends formed with a knuckle having a rounded edge adapted to engage with the rounded side of the pocket, means comprising a pin passing through the socket and engaging the grooves in the confronting faces of the knuckles for retaining the knuckles in the pocket, rope slips comprising each a substantially rectangular member having one of its faces grooved longitudinally and received in confronting depressions in the inner faces of the jaws, 20 means integrally formed with the said slips and with the said jaws for retaining the slips in the said grooves, and means comprising an oppositely pitched screw engaging with elements associated with the jaws 25 for relatively adjusting the jaws. 30
3. A clamp for the purpose set forth including a back, a pair of jaws each having one of their ends removably and hingedly connected with the back, grooved rope slips 40 in the confronting faces of the jaws, said jaws being centrally slotted at their outer edges and being provided with concaved enlargements extending in opposite directions from the said slots, a T-shaped member 45 within each of the concavities and having its central portion disposed in the slot, one of said jaws beyond its referred to concaved portion having its edges formed with outstanding elements, a hinge bolt passing through the ears and engaging in the opposite ends of the T associated with said jaw, guide rods connected with the bolts and passing through openings in the longitudinal member of the other T, the central member of both of the T's having bores and having threads disposed at opposite pitches, an oppositely pitched bolt engaging with the threads in the said bores, and a handle for the bolt. 50
4. A clamp for the purpose set forth, including a back member having a central pocket, jaws having their ends provided with knuckles received in the said pocket to hingedly connect the jaws with the said back member, means for retaining the knuckles in the pocket, T-shaped members pivotally connected with the jaws and provided with sockets, means for retaining the sockets in alinement, and an adjustable element co-engaging with the said sockets. 60
5. A clamp for the purpose set forth comprising, a back member having a central pocket, jaws having one of their ends provided each with a knuckle received in the said pocket to hingedly connect the jaws with the back member, means, between said jaws, for retaining the knuckles in the socket, each of said jaws having its confronting face provided with oppositely disposed rectangular slots, the inner wall of 65 each of the slots being notched, and the side walls of the slots, at one of the ends thereof, having incut depressions, rope slots designed to be received in the said slots to engage with the notch and depressions to retain the 70 said slots upon the jaws, and means, upon the outer ends of the jaws, for adjusting the 75 said jaws with respect to each other. 80
- In testimony whereof I affix my signature.
BENJAMIN F. KELLEY.
